UNITED STATES PATENT OFFICE.

ADAM D. LUGIBIHL AND HECTOR KIBELE, OF BLUFFTON, OHIO.

DESIGN FOR A FAUCET-SOCKET AND WINDOW-FRAME FOR CREAM-SEPARATORS.

SPECIFICATION forming part of Design No. 33,862, dated January 8, 1901.

Application filed August 25, 1900. Serial No. 28,080. Term of patent 7 years.

To all whom it may concern:

Be it known that we, ADAM D. LUGIBIHL and HECTOR KIBELE, citizens of the United States, residing at Bluffton, in the county of Allen and State of Ohio, have invented and produced a new and original Design for a Faucet-Socket and Window-Frame for Cream-Separators, of which the following is a specification, reference being had to the accompanying drawings, forming a part thereof.

Figure 1 is a side elevation of an attachment for cream-separators, showing our new design; Fig. 2, an edge view of the same; Fig. 3, an edge view of Fig. 1 looking downward.

As shown in the drawings, the leading or material feature of our design consists in a faucet-socket and window-frame having a body portion, in which is formed a pair of holes or openings, together with a raised annular flange having tapering projections substantially diametrically opposite each other, with rounded outer ends.

The letter A represents the body portion having a pair of annular holes or openings B and C, respectively, therein, the opening B having an annular ring or bead D therein constituting a rounded rib. This rounded rib forms a finish between a glass E and the

body portion A. About the hole or opening C is formed a raised annular projection F, 30 which also curves into the body portion A and extends out substantially even with an annular flange G. This annular flange has a tapered projection H, having rounded ends, as shown at I, extending from substantially 35 diametrically opposite sides of the flange in a radial direction. As viewed in Figs. 2 and 3, it will be seen that between the body A and the flange G is formed a space J. It will also be observed from Figs. 2 and 3 that the 40 rear edge of the body portion is curved, as shown at K.

Having thus fully described our invention, what we claim as new, and desire to secure by Letters Patent, is—

The design for a faucet-socket and window-frame for cream-separators, substantially as herein shown and described.

In testimony whereof we have signed our names to this specification in the presence of 50 two subscribing witnesses.

ADAM D. LUGIBIHL.
HECTOR KIBELE.
